Primary Examiner — L. A. Grabenstetter

(57) **CLAIM**

The ornamental design for a case for mobile phone as shown and described.

DESCRIPTION

1. Case for mobile phone

1.1 is a front view of a case for mobile phone showing our new design;

1.2 is a back view thereof;

1.3 is a left view thereof;

1.4 is a right view thereof;

1.5 is a top view thereof;

1.6 is a bottom view thereof;

1.7 is a top, front and right side perspective view thereof;

1.8 is a top, back and left side perspective view thereof; and

1.9 is a bottom, back and right side perspective view thereof.

The broken lines in the drawings depict portions of the case for mobile phone that form no part of the claimed design.

1 Claim, 9 Drawing Sheets
